UNITED STATES PATENT OFFICE.

WILLIAM WATSON CAMP, OF SMITHVILLE, CANADA.

ACETYLENE-GAS APPARATUS.

SPECIFICATION forming part of Letters Patent No. 669,741, dated March 12, 1901.

Application filed August 25, 1898. Serial No. 689,513. (No model.)

To all whom it may concern:

Be it known that I, WILLIAM WATSON CAMP, of Smithville, in the Province of Ontario and Dominion of Canada, have invented a new and Improved Gas Apparatus, of which the following is a full, clear, and exact description.

My apparatus is of that class of gas-making apparatus which uses an excess of liquid within which a small amount of gas-forming material—such as carbid of calcium, for example—is inserted, as necessitated by the consumption of the gas. The generator and gasometer are preferably made separate, but connected, and the insertion of the gas-forming material is controlled by the fall of the gasometer-bell. The generator is in the form of a bell, its lower edge extending into a tank of water for keeping the generator supplied and forming a seal to prevent the escape of the gases which are formed in said generator. Preferably this water-tank has an open top and is integral with the generator, and the cans of gas-forming material are introduced through said tank and under the edge of said generator.

Reference is to be had to the accompanying drawings, forming a part of this specification, in which similar characters of reference indicate corresponding parts in all the views.

Figure 1 is a side elevation of my device with a portion of the generator in section. Fig. 2 is a cross-sectional elevation taken upon the line 2 2 of Fig. 1. Fig. 3 is a sectional elevation taken through the generator-tank, showing one of the carbid-holders being inserted beneath the partition. Fig. 4 is a top plan view with the guides in section, showing the mechanism for controlling the insertion of carbid. Fig. 5 is a perspective view showing the trip mechanism for regulating the control of the carbid, and Fig. 6 is a sectional elevation in perspective of the carbid-holder.

The gasometer is of the usual form, consisting of a tank A, open at the top, and a gasometer-bell A', which is open at the bottom and fits within the tank A, the latter tank being filled with water, which forms a seal. The upper tank or bell A' is provided with the guide-pulleys A³, running upon guide-bars A², attached to the tank A and

extending upward therefrom. The gas is drawn from the gasometer through the pipe C² and is discharged into the gasometer from the pipe C, which connects with the generator.

The generator consists of a tank B, having a vertical partition b, extending across the upper portion thereof. This partition is located near the middle of the tank and terminates at some distance from the bottom of the tank, leaving a space beneath it, through which the carbid-holder may be passed from one side to the other. That portion of the tank on one side of the partition b is open at the top. The other portion is provided with a cover b', which makes an air-tight connection with the partition b and one wall of the tank. This portion of the tank in effect forms an inverted bell adapted to collect the gas as it is generated. This bell might be constructed independent of the tank, if so desired; but the construction described is preferred. The pipe C, which delivers the gas to the gasometer, is connected to the upper portion of the bell and is also provided with the valve C', by means of which it may be closed, so as to permit inspection or cleaning of the generator without loss of gas from the collector. The tank and the bell are filled or nearly filled with water.

Upon one side of the open section of the tank opposite the bell or partition b which forms the bell are a series of vertically-extending guides H. Mounted to slide upon these guides are a series of weights G², each provided with outwardly-extending arms G³, to which are pivotally attached links G'. The opposite ends of said links are pivotally attached to an arm or base G, adapted to be secured in any convenient manner to the outer cylinder of the carbid-holder D. This arm or base G has a hook g extending outward beyond the carbid-holder. As herein shown, the device is provided with six of these weights G² and is adapted to hold six carbid-holders. The number which is to be used is dependent entirely upon the conditions in each case. Each of these carbid-holders D is maintained in its upper position, as shown in Fig. 2, by a pivoted bar or plate F. This bar is pivoted upon a rod F', which extends back of the guides H. The plate F is maintained in its horizontal position by means of

a spring-catch f , which is pivoted upon a rod f^2 and is held downward against the bar F by means of a spirally-coiled spring f' , which is secured at one end to the rod f^2 and at the 5 other to the catch f . The depression of the catch f is limited by a rod f^3 , which extends across the device. The rear end of the plate F extends to a point immediately above the pivot-rod f' of the catch f , so that the plate 10 f and its connection with the rod f' acts as a hook to hold the plates F and E . Spring f^2 does not have to support the weight of the holder D . By supporting the carbid-holders independently of each other I secure evident 15 convenience in inspection and handling for purposes of repair or filling and emptying, &c.

Extending across the device back of the guides H is a bar I , to which are attached a series of guide-rods J and J' . These rods extend 20 vertically, the rods J extending upwardly from the bar I and the rods J' extending downwardly therefrom. These rods are arranged in pairs, the rods J' lying close alongside of and practically in contact with the 25 edge of the catch f . The rods J are separated from the rods J' a distance which is immaterial, so long as it permits the passage of the arm K between. The upper ends of the lower rods J' extend above the catch f , and 30 the lower ends of the rods J terminate above said catch, but below the upper ends of the rods J' .

Attached to and moving with the rising-and-falling gasometer-bell is a horizontal bar 35 K , which is alongside of the guide-rods J and J' . Upon this bar K is mounted a trip K' , consisting of a frame surrounding the bar K and having a small wheel K^3 journaled therein and running upon the upper edge of the 40 bar K . This trip has an arm extending downwardly and terminating in a side extending pin k . This pin goes far enough to one side to engage the rods J and J' . The trip K' is caused to move along the bar F by having a 45 cord K^2 attached thereto, said cord extending horizontally over a guide-pulley and having a weight K^4 attached to the lower end thereof. This weight is sufficient to cause the trip to travel along the bar K .

50 When the gasometer-bell is in its upper position, the pin k is in engagement with one of the rods J and slides up and down upon the same as the gasometer rises and falls. When the gasometer-bell falls to a certain point, the pin k will pass beneath the lower end 55 of the rod J . The trip is freed from the rod J and is drawn along the bar K until the pin strikes the rod J' . The pin is thus placed immediately over the catch f . The further 60 descent of the gasometer-bell will cause the pin to depress one end of the catch f and finally to release the bar F , which supports the carbid-holder. When the carbid-holder is released, it drops into the open portion of the 65 generator-tank. The weight G^2 is sufficient to cause the carbid-holder to sink until the hook g thereof comes in contact with the rod

F^2 , which extends across the generator-tank close to the bottom edge of the partition b . When the hook g engages the rod F^2 , the further descent caused by the weight G^2 causes the carbid-holder D to swing laterally, as shown in Fig. 3. This movement is continued until the weight descends to the position indicated in Fig. 2. This forces the carbid-holder beneath the partition b and upward into the bell formed by the inclosed portion of the tank, its lower edge being substantially in the plane of the lower edge of the partition or seal b , so that the gases formed even 80 when most active will have no lateral escape into the tank B' .

The gas generated by the decomposition of the carbid is first collected by the bell and delivered through the pipe C to the gasometer. 85 The gasometer-bell then rises until the pin k passes above the upper end of the rod J' . The weight K^4 upon the end of the cord K^2 causes the trip K' to travel along the bar K until it comes in contact with the next one of the rods 90 J . It will then travel up this rod as the gas is generated, and then down as it is consumed. In this way the catches f for the various carbid-holders are tripped in succession, and the generator is charged anew.

The carbid-holders are of a peculiar construction, as shown clearly in Fig. 6. The inner portion of the carbid-holder consists of a cylinder D' , having a tight bottom and having a large number of holes or perforations 100 formed in the sides thereof. Over the lower portion of this cup is fitted a second cup or cover D^2 . This cover fits closely upon the cup D' and extends downwardly, preferably about two-thirds the length of the lower cup. 105 The top or end of this cover is provided with a hole d , through which the gas may readily escape. This hole is surrounded by an exterior circular band d' , which is provided with a series of perforations d^2 near its upper edge 110 and adapted to permit the passage of the gas. Outside of this inner portion of the carbid-holder is a loosely-fitting cylinder E . This extends the entire length of the inner holder and is open at both top and bottom. The 115 upper end of this outer cylinder is closed, however, by a conical cap E' . The lower portion of this cap is made of a cylindrical shape and fits closely over the upper end of the cylinder E . A packing-ring E^2 , of rubber or any 120 suitable packing material, is placed between the cylindrical portion of the conical cap and the upper end of the cylinder. This makes an air-tight connection between the two and permits of a slight motion of the cap upon 125 the cylinder. This motion is limited by means of the staples e' and the links or hooks e , the former being secured to the cylinder E and the latter to the cap E' .

The carbid-holders are secured to the arm 130 or base G , as previously mentioned and in an inverted position, the conical cap being down. When inserted in the generator, the position is reversed, the conical cap being

upward. When inserted beneath the water, the water will enter the carbid-holder and cause generation of the gas. The cap E' will fill with gas, and its buoyancy will act to hold 5 the carbid-holder up to the desired level in the generator. The air contained in it at the time of its introduction will of course have the same effect. The carbid being inclosed within a holder which may be readily removed, the lime caused by the decomposition of the carbid will be retained in the holder and removed with the holder, so that the generator will not become filled with a deposit of lime.

15 When the machine is put in operation or after the holders have all been filled, the trip K' is moved to the farther end of the guide-bar. As the gas is consumed the trip will move along and in succession cause the insertion of each of the carbid-holders. The holders are filled and returned to their original position by hand.

It is evident that the generator-tank may be made as a circular or annular tank surrounding the gasometer when desired. This is only the substitution of a circular form for a straight form. The mechanism by which the same is operated will not vary from the mechanism described heretofore.

30 It is evident that my generator is equally of use in the manufacture of other gases which are formed by introducing a gas-making material into a liquid.

Having described an apparatus embodying 35 my invention in what appears to me its most practical form, I claim the following-defined novel features, all substantially as set forth:

1. In a gas-making apparatus, the combination of a tank for the liquid, a generating-40 tank, a sealed communication between said tanks, a gasometer, means operated by said gasometer for introducing the gas-forming material into the generating-tank, and means for preventing the formation of gas outside 45 of said generating-tank during such introduction.

2. In a gas-making apparatus, the combination of a tank for the liquid, a generating-50 tank, a sealed communication between said tanks, a gasometer, a holder for gas-forming material, and means operated by said gasometer for introducing said holder into said generating-tank.

3. In a gas-making apparatus, the combination of a tank for the liquid, a generating-55 tank, a sealed communication between said tanks, a gasometer, means operated by said gasometer for introducing the gas-forming material into the generating-tank, and means 60 for preventing the escape of gas through said seal.

4. In a gas-forming apparatus, the combination of a tank for the liquid, a generating-65 tank, a sealed communication between said tanks, a gasometer, means operated by said gasometer for introducing the gas-forming material into the generating-tank, and means

for elevating said gas-forming material so as to prevent the formation of gas below the level of said seal.

5. A gas-making apparatus, comprising a tank for the liquid, a generating-tank open at the bottom and extending into the liquid in the liquid-tank, a holder for the gas-forming material normally supported outside of 75 the liquid-tank, a weight adapted to immerse the holder and carry it beneath the generating-tank, means normally holding the weight and holder raised, and means automatically releasing the same.

6. A gas-making apparatus, comprising a tank for the liquid, a generating-tank open at the bottom and extending into the liquid in the liquid-tank, a holder for the gas-forming material normally supported outside the liquid-tank, a weight adapted to immerse the holder and carry it beneath the generating-tank, and a catch normally holding the weight and holder raised and released by the descent of the gasometer.

7. In a gas-making apparatus, an open-topped water-tank, a gas collector or bell open at the bottom and extending into the water at the tank, a holder for gas-forming material normally supported outside the tank, a weight 95 mounted to slide on guides and connected with the holder, said weight being adapted to immerse the holder and carry it beneath the bell, and a catch normally holding the weight raised and released by the descent of the gas-100 ometer.

8. In a gas-making apparatus, an open-topped water-tank, a gas collector or bell open at the bottom and extending into the water of the tank, a holder for gas-forming material 105 normally supported outside the bell, a weight mounted to slide on guides, a link connecting the weight with the holder, and a catch adapted to engage the holder in its descent and to swing it under the bell.

9. In a gas-making apparatus, an open-topped water-tank, a gas collector or bell open at the bottom and extending into the water in the tank, a vertical guide extending down into the tank, a weight mounted to slide thereon, a link pivoted to the weight, a clamp or base adapted to secure the holder for the gas-forming material and pivoted to the link, said holder, and a catch adapted to engage the clamp or base in its descent and to swing the 120 holder beneath the bell.

10. In a gas-making apparatus, an open-topped water-tank, a gas collector or bell open at the bottom and extending into the water in the tank, a vertical guide extending down 125 into the tank, a weight mounted to slide thereon, a catch normally holding the weight raised, a link pivoted to the weight, a clamp or base adapted to secure a holder for the gas-forming material thereto and pivoted to the link, 130 said holder, a catch adapted to engage the clamp in its descent and to swing the holder beneath the bell, and means for freeing the catch by the descent of the gasometer-bell.

11. A holder for gas-forming material having a gas-tight buoyant portion adapted for holding it up to a desired point.
12. A holder for gas-forming material having a hollow gas-tight portion for adding buoyancy thereto, whereby said holder is continually maintained at a desired point.
13. A holder for gas-forming material having a chamber therein for receiving a portion of the gas and retaining the same, and means for permitting said chamber to expand.
14. A holder for gas-forming material, comprising a cup having perforated sides, a cap fitting tightly over the cup and having gas-escape apertures therein, and a second cup fitting loosely over the perforated cup and its cap.
15. A holder for gas-forming material, comprising a cup having perforated sides, a cap fitting tightly over the cup and having gas-escape apertures therein, and a second cup fitting loosely over the perforated cup and its cap, and consisting of two parts, a cylinder, and a conical cap closely fitting one end of the cylinder and having a longitudinal movement thereon.
16. A gas apparatus, comprising a generator-tank having a vertical partition extending across the upper portion thereof, that portion of the tank on one side of the partition being covered and forming a gas collector or bell, a series of holders for gas-forming material temporarily supported above the open part of the tank, a rising-and-falling gasometer, and means operated thereby for successively immersing the holders and carrying them beneath the partition.
17. A gas apparatus, comprising a rising-and-falling gasometer, a frame alongside thereof, a series of levers pivoted on the frame and adapted to support a charge of gas-forming material, a catch normally holding the levers up, a horizontal bar mounted on the gasometer-bell, and a trip mounted to slide on the said bar and having a step-by-step movement upon said bar, whereby it is adapted to successively engage the trips and free a charge of gas-forming material at each descent of the bell.
18. A gas apparatus, comprising a rising-and-falling gasometer, a frame alongside thereof, a series of levers pivoted on the frame and each adapted to support a charge of gas-forming material, a catch normally holding the levers up, a horizontal bar mounted on the gasometer-bell, a trip mounted to slide on said bar, a cord and weight attached thereto, a pair of trip-controlling rods for each trip, said rods slightly overlapping and being laterally separated, the lower end of the upper and the upper end of the lower being above the catch, and a side extending arm on the trip engageable with both rods, whereby the trip is caused to successively engage the catches and free the holders for gas-forming material.
